UNITED STATES PATENT OFFICE

DAVID B. ROBERTS, OF HARTFORD, CONNECTICUT

OIL BURNER

Application filed January 21, 1928. Serial No. 248,483.

Automatic oil burners, especially but not exclusively of the type adapted for household use, are usually operated intermittently by an electric motor. This motor is so controlled as to start and stop automatically and only when the motor is running is there any combustible mixture delivered to the fire box. This means that the fire goes out completely during the period of stoppage and there therefore must be some means provided to ignite the fuel when the motor starts.

This is usually done either by the use of a gas pilot flame or by electrical means such as the producing of a spark in a spark plug. The electrical means is preferable to the gas means as there is already electrical current supplied to operate the motor and it is therefore not necessary to do any piping as for gas.

The main difficulty with electric ignition has been a tendency of the spark plug electrodes to corrode or become dirty, both thru the action of the electric arc and thru the deposit of carbon from the combustion of the fuel. It has also been difficult to produce a spark hot enough and large enough to ignite the fuel without excessive current consumption. A third difficulty lies in the fact that there is one particular position with reference to the discharge nozzle in which the ignition means should be placed to produce the best results. Owing to the different sizes and types of furnaces in which such oil burners are placed it is generally necessary to make adjustments of the nozzle position while installing and with the spark plug where electrical ignition means are separate from the nozzle it also necessitates adjustment of the ignition and due to lack of skill in installation the best possible position for the ignition is not usually obtained.

My invention consists in an improved method of electric ignition whereby,

1st. The electrodes, particularly the negative electrode, which is the one which gets foul, is self-cleansing and provides an infinite number of spark points instead of one point as in the ordinary type of spark plug.

2nd. By the peculiarity of its construction provides for drawing out the electric arc and

making what virtually amounts to a flaming arc.

3rd. Provides a positive location for the electrodes in relation to the fuel discharge nozzle.

My invention is described in the following drawings which form a part of this specification but it is understood that I do not limit myself to the specific construction shown.

In the drawings,

Fig. 1 is a front elevation in vertical section with parts in elevation of a boiler and oil burning unit.

Fig. 2 a plan view of one type of disc electrode.

Fig. 3 a plan view of another type of disc electrode.

Referring to the drawings the pump unit 10 is supported by springs 11 on base plate 12 which is inserted in the ash pit 13 of the furnace. The base plate 12 also supports by means of adjustable legs 14 the plate 15 which is located between the fire box 16 of the furnace and the ash pit 13 and which serves as a support for building up a fire clay retaining wall 17. Plate 15 also supports a number of plates 18 so arranged as to permit the free passage of air from the ash pit to the fire box and at the same time provide a baffle preventing the flame from the fire box passing down into the ash pit.

The pump unit 10 has as a bottom plate the oil reservoir 19 to which the mixture of oil and air is pumped by the spiral gears 20 and 21 which in turn suck the oil and air mixture from a carburetor, which, as it forms no part of the claim, is not shown. The top plate 22, see Fig. 1, of the pump unit 10 supports a motor 220 which has for an armature shaft a hollow shaft 23 to one end of which is keyed the pump driving gear 20. Telescopically arranged in the hollow shaft 23 is a tube 24 which may be adjusted for height and clamped in the desired position by clamp nut 95. The combustion mixture is forced by pressure by the pump from chamber 19 up thru hollow shaft 23 and tube 24 to nozzle 26 where it escapes in the form of a spray thru port 27.

Permanently fixed to tube 24 by means of nozzle 26 and nut 28 is electrode disc 29 which by its location is permanently fixed at a definite distance from nozzle ports 27, and as tube 24 and nozzle 26 revolve with the motor shaft disc 29 also revolves with them. This disc may be either of a smooth periphery as shown in Figure 4 or may have its periphery serrated as shown in Figure 5. Located at 10 the proper distance from the disc 29 is electrode 30 which is supported by rod 31 which is threaded into stud 32 inclosed in insulating cylinder 33 which is clamped to leg 14. Fastened to stud 32 by binding post 35 is the 15 wire 34 from the source of electric supply, the other wire of the circuit being grounded by binding post 36 to motor frame 22. This circuit closes when the motor starts and opens after it has run a certain length of 20 time, but as this thermal relay does not form any part of my claim no further description is appended.

The operation is as follows: When the motor starts tube 24 is revolved and a combustible mixture of oil and air is forced out thru nozzle 26 into the fire box 16. At the same time current is supplied to electrode 30 and jumps to disc 29 which as it is rapidly revolving draws out the spark into a flaming arc and ignites the mixture. Current is then automatically shut off from electrode 30. The revolving disc 29 not only presents an infinite number of points for formation of the arc and draws out the arc into a flame 35 but also by means of its rotary motion cleanses itself.

I therefore claim:

In an electric ignition for oil burners, the combination of a fixed electrode, a rotating 40 nozzle tube, a nozzle, a disc electrode fastened to said nozzle tube in a definite and permanent relation to the nozzle opening, including a hollow shaft to rotate the nozzle tube, a pump connected to one end of said shaft and 45 means for adjustably locating said nozzle tube in said shaft.

In testimony whereof I hereunto affix my signature.

DAVID B. ROBERTS.
